CLAIM

The ornamental design for food container, as shown and described.

DESCRIPTION

FIG. 1 is a perspective view of a food container in accordance with the present design;

FIG. 2 is a front view of the food container of FIG. 1, a rear view being a mirror image thereof;

FIG. 3 is a right-side view of the food container of FIG. 1, a left-side view being a mirror image thereof;

FIG. 4 is a top view of the food container of FIG. 1; and, FIG. 5 is a bottom view of the food container of FIG. 1. The broken lines shown represent unclaimed subject matter and form no part of the claimed design.

1 Claim, 5 Drawing Sheets(56)
